UNITED STATES PATENT OFFICE

162,145

EMBOSSED LEATHER OR SIMILAR ARTICLE

Adele Q. Freedman, New York, N. Y.

Application August 24, 1950, Serial No. 11,907

Term of patent 14 years

(Cl. D87—3)

To all whom it may concern:

Be it known that I, Adele Q. Freedman, a citizen of the United States of America, residing in New York, county of New York, and State of New York, have invented a new, original and ornamental Design for an Embossed Leather or Similar Article, of which the following is a specification, reference being had to the accompanying drawing, forming part thereof.

The figure on the drawing is a surface view of an embossed leather or similar article, showing my new design.

The design unit is outlined by broken lines and is repeated over the surface of the embossed leather as indicated.

I claim:

The ornamental design for an embossed leather or similar article substantially as shown and described.

ADELE Q. FREEDMAN.
